UNITED STATES PATENT OFFICE.

CHARLES E. SMITH, OF CAMBRIDGE, NEW YORK.

BAND-LAMP SUPPORT.

SPECIFICATION forming part of Letters Patent No. 443,212, dated December 23, 1890.

Application filed July 28, 1890. Serial No. 360,174. (No model.)

To all whom it may concern:

Be it known that I, CHARLES E. SMITH, a citizen of the United States, residing at Cambridge, county of Washington, and State of New York, have invented certain new and useful Improvements in Band-Lamp Supports, of which the following is a specification.

My invention relates to such improvements; and it consists of the novel construction and combination of parts, hereinafter described and subsequently claimed.

Reference may be had to the accompanying drawings, and the letters of reference marked thereon, which form a part of this specification.

Similar letters refer to similar parts in the several figures therein.

Figure 1 is a view in front elevation of my improved band-lamp support in position for use, a part of the form of the wearer being outlined by dotted lines. Fig. 2 is a top plan view of the wire support detached when occupying the same position shown in Fig. 1. Fig. 3 is a vertical section of the wire support, taken on the broken line 3 3 in Fig. 1, a portion of the lamp being shown by solid lines.

A single wire A is bent to form the approximately horizontal bend A', the loops A², and the terminal depending legs A³ and A⁴. The lower ends of the legs are each secured to a strap or belt B, adapted to be buckled around the chest of the wearer, as shown in Fig. 1, so that the bend is supported in a position just above the shoulder, as shown partly by dotted lines. The looped arm of the bend is preferably longer than the other arm, and is also connected with the belt by short adjustable straps B' at the back. The upper ends of the straps are secured in the loops, which serve to prevent them from slipping lengthwise of the arm while in use.

The connecting-straps serve to retain the wire support firmly in place upon the shoulders of the wearer, and their adjustability, as well as the adjustability of the belt, permits the support to be readily fitted to different-sized persons. By having the arms of the bend between the bend and the depending legs of unequal lengths the supporting-

legs are separated from each other and afford 50 to the horizontal bend a stable support.

The lamp may be secured to the bend in any known manner. I have shown a horizontal slot C in the depending flange or base C' of the lamp C², adapted to receive the 55 bend. The lamp shown by dotted lines C² in Fig. 1 is slid onto the bend, as shown in Figs. 1 and 3, where it may be held by the friction of the wire upon the slot-walls, or in any known manner, the bend forming a holder 60 for the lamp.

By constructing the supporting device partly of wire and partly of flexible straps I am able to impart to it the necessary rigidity when in use and to fold it into a small space 65 for transportation when not in use. The length of the depending wire legs and the connecting-straps is such as to hold the front and rear portion of the belt above the parts passing under the arms, which prevents an 70 uncomfortable pressure upon the chest when the lungs are inflated.

I do not wish to be limited to the exact form shown for the wire support, nor to a single integral wire.

The leg A⁴ may be connected directly with the longer arm of the lamp-holder A', as shown by dotted lines A⁵ in Fig. 2, and the holder-bend A' turned up to a vertical position to engage with the side of the lamp, as 80 shown by dotted lines A⁶ in Fig. 1.

When desired, one or both of the arms of the bend may be provided with a notch D, adapted to receive the flange-edges formed in the base of the lamp by the slot C.

What I claim as new, and desire to secure by Letters Patent, is—

1. As a new article of manufacture, a band-lamp support consisting of a lamp-holder which occupies a position above the shoulder 90 when in use, depending lugs connected at their upper ends with the holder at unequal distances from the shoulder, and a belt connected on one side with the lower ends of the depending legs and on the opposite side with 95 the holder by a connecting-strap, substantially as described.

2. In a band-lamp support, the combination,

with a lamp-holder having a supporting-arm and depending legs connected at their upper ends with the supporting-arm at unequal distances from the lamp-holder, of an adjustable belt connected with the lower ends of the legs, and a strap connection between the belt and the supporting-arm, substantially as described.

In testimony whereof I have heretinto set my hand this 25th day of July, 1890.

CHARLES E. SMITH.
